UNITED STATES PATENT OFFICE.

WALLACE L. CLAY, OF THE UNITED STATES ARMY, AND ANDREW H. HALLOWELL, OF FRANKFORD, PENNSYLVANIA.

SPOT-LIGHT BULLET.

1,337,343.

Specification of Letters Patent. Patented Apr. 20, 1920.

Application filed January 30, 1919. Serial No. 274,077.

(FILED UNDER THE ACT OF MARCH 3, 1883, 22 STAT. L., 625.)

To all whom it may concern:

Be it known that we, WALLACE L. CLAY, Lieut. Col., Ordnance Department, U. S. A., at present stationed at Frankford Arsenal, 5 and ANDREW H. HALLOWELL, resident of Frankford, Montgomery county, Pennsylvania, both citizens of the United States, have jointly invented an Improvement in Spot-Light Bullets, of which the following 10 is a specification.

The invention described herein may be used by the Government, or any of its officers or employees in prosecution of work for the Government, or by any other person 15 in the United States, without payment of any royalty thereon.

This invention relates to a device for denoting the location of an objective for a fire arm, to enable a gunner to so aim or add 20 just the fire arm as to accurately place the shot, and has for one of its objects to provide a device adapted to be projected from a fire arm and capable, when it strikes an obstruction, of emitting a vapor like cloud 25 and a flash of light, the vapor being visible when the device is fired in the daytime and the flash visible when fired at night.

Another object of the invention is to provide a device of this character having means 30 whereby the vapor and light producing element is forced from the projectile by the force generated by the impact against an obstruction.

With these and other objects in view the 35 invention consists in certain new and useful construction and combination of parts as will herein-after be more fully described and pointed out in the claims.

In the drawings—

40 Figure 1 is a longitudinal sectional elevation.

Fig. 2 is a longitudinal section of the jacket portion of the improved device.

45 Fig. 3 is a view of the movable base plug from one side.

Fig. 4 is a view of the movable base plug at right angles to the view shown in Fig. 4.

The improved device comprises a jacket represented as a whole at 10, and including 50 a pointed forward end 11.

The jacket is formed initially with its rear end open as shown in Fig. 2, and provided with a base plug, the plug being secured in place by "spinning" the material of the

jacket over its rear end as shown at 13, after 55 the charge indicated at 14 has been inserted.

The plug is further secured in place by a cap 15 of solder or the like, to prevent deformation when fired.

At its forward end the plug 12 is reduced 60 or wedge shaped as represented at 16, and is constantly embedded at its reduced end in the "charge" 14.

The reduction of the forward end of the plug also produces chambers or cavities 17 65 into which the material of the "charge" 14 may expand due to the heat generated by the passage of the device through a gun barrel.

A plurality of apertures 18 are formed 70 through the reduced portion 11 a short distance rearwardly of the "nose," and initially closed by a substance which is fusible under relatively low temperature, for instance a "soft" solder, and in practice a compound is 75 employed whose melting point is such that it will be partly melted by the heat generated by the passage of the device through the barrel of the gun but will not melt out until the device reaches its objective when the impact will jolt the partly melted closures from the apertures and permit the phosphorus or other "charge" substance to vaporize and escape through the apertures as a visible smoke like emanation by daylight 80 and a flash by night. By this means the point of impact is disclosed to the gunners either by daylight or at night.

At the moment of impact the base plug 12 will be detached from the cap 15 and thrown 90 toward the forward or pointed end of the jacket, and operates as a "plunger" to force the "charge" 14 through the apertures, and thus materially increase the efficiency and utility of the device.

95 The jacket 10 may be of any required size and capacity and thus adaptable to gun barrels of any gage.

By employing the improved device the gunner is able to accurately locate an objective and thus control the firing and accurately place the projectiles without loss of time or waste of ammunition.

Having thus described the invention what is desired to secure by Letters Patent is: 105

1. A device of the class described comprising a pointed jacket having gas escape apertures adjacent to its pointed forward

- end closed by fusible elements, a base plug weakly secured within the rear of the jacket, and a charge in the body of the jacket of a substance capable of ejecting a visible vapor 5 and a flash of light through the apertures.
2. A device of the class described comprising a pointed jacket with apertures in the pointed portion near the forward end and adapted to contain a medium capable 10 of producing visible vapor and a flash of light when exposed to the air through the apertures, and a plug weakly secured in the rear end of said jacket having a wedge-shaped forward end.
- 15 3. A device of the class described including a jacket adapted to contain a substance capable of ejecting visible vapor and producing a flash of light, said jacket having lateral openings, closures for the openings 20 which are partially fusible by the heat generated by the passage of the projectile through a gun barrel and adapted to be ejected by the impact of the projectile against its objective, and a plug weakly secured within the jacket in constant contact 25

with the vapor and light producing substance and movable longitudinally of the jacket upon said impact to force the vapor and light producing substance through the apertures.

4. A device of the class described including a jacket adapted to contain a substance capable of ejecting visible vapor and producing a flash of light, said jacket having lateral openings, closures for the openings 30 which are partially fusible by the heat generated by the passage of the projectile through a gun barrel and adapted to be ejected by the impact of the projectile against its objective, and a plug weakly secured within the jacket and reduced at the forward end, said plug being in constant contact at its forward end with the vapor and light producing substance and movable upon said impact longitudinally of the 35 jacket to force the vapor and light producing substance through the apertures.
